STARCH MANUFACTURING PROCESS

Albert Peltzer, Jr., Palo Alto, Calif., assignor to
 Merco Centrifugal Separator Co. Ltd., San
 Francisco, Calif., a corporation of California

Application July 31, 1933, Serial No. 682,909

7 Claims. (Cl. 127—69)

This invention applies generally to systems for the manufacture of starch from materials like corn, where the corn or like material is disintegrated and components such as germs, hulls, 5 fibrous material and gluten, are removed from the desired starch.

It is an object of the invention to provide an improved process or method for the removal of gluten from wet starch bearing feed material 10 such as is produced in systems of the above character, thereby making possible the manufacture of starch having a relatively low protein content. In carrying out my invention a step of flotation separation is utilized, and this step is made effective 15 by the prior removal of fibrous material. Furthermore foaming or frothing is accomplished in a separating step prior to flotation, and simultaneously with removal of fibrous material.

Further objects and features of the invention 20 will appear from the following description in which the preferred embodiments of the invention are set forth in detail in conjunction with the accompanying drawing.

Referring to the drawing:

Figure 1 is a diagrammatic view showing one 25 way in which my process may be carried out in practice.

Fig. 2 is a diagrammatic view showing a modified manner for carrying out the process.

The process or method of the present invention 30 in its preferred form can be outlined briefly as comprising subjecting wet starch bearing material to centrifugal separation, in such a manner that fibrous material therein passes out with the 35 gluten overflow, and the starch underflow is foamed or frothed to a substantial degree. Further removal of gluten from this starch underflow is then accomplished by flotation.

The process can be better understood after a 40 brief description of the drawing. Referring first to Fig. 1, I have indicated a centrifuge of the type disclosed in copending application Serial No. 586,773, filed January 13, 1932. A centrifuge of this character is characterized by the fact that 45 it operates continuously, and a portion of the underflow is continually returned to the centrifuge bowl adjacent the periphery thereof. Thus, in the diagrammatic representation the centrifuge bowl 11 is provided with a separating chamber 12 into which the wet starch bearing feed material is introduced as indicated by line 13. A starch underflow discharges from peripheral nozzles 14 and is received by volute 16, while a gluten 50 overflow discharges over the weir 17. A major 55 part of the material discharged from the noz-

zles 14, after further removal of gluten therefrom as will be presently explained, is continuously returned back into the centrifuge chamber as indicated by line 18. The material returned to the centrifuge rotor by way of line 18 is delivered 5 into the bowl at a point adjacent the periphery thereof, thru an impeller 20.

Wash liquor can be introduced into the rotor together with the return, as indicated by line 19. The use of a filtrate obtained from other points 10 in the wet starch system is desirable, since such a filtrate promotes foaming.

With a centrifuge of the type described above, where the feed material consists chiefly of starch together with gluten and fibrous material (commonly termed "mill starch"), the overflow 15 consists of gluten together with fibrous material from the feed. The underflow received by the volute 16 consists of starch which still retains a part of the gluten from the feed, but which will be substantially free from fibrous material. Furthermore although the feed material may not be foamed or frothed to any material degree, the underflow will be foamed or frothed to a substantial extent. This foaming action is attributed 20 to the entrance of air or other gases with the feed, and to introduction of air into the return circuit because of jetting into volute 16, and the beating and violent agitation to which the material is subjected. I have found that the foamed 25 or frothed condition of the underflow facilitates a subsequent separation of remaining gluten from the starch, by flotation. Thus as shown in Fig. 1, the starch underflow removed from volute 16 is introduced into a vessel 22 by way of pipe 21. 30 Gluten separated from the starch in vessel 22 is floated off over weir 23, while the starch is removed by way of stand pipe 24 and outflow box 26. A rotating skimmer 27 can be employed adjacent to weir 23, to secure more effective removal 35 of the gluten. A continuous return of starch to the centrifuge is afforded by pipe 18a, which is an extension of line 18. Suitable baffling can be provided for the discharge from pipe 21 and the inlet end of pipe 18a, as illustrated. 40

The removal of gluten from the underflow by flotation has been found to be highly effective. The substantial absence of fibrous material in the centrifuge underflow eliminates a middle draw-off from the flotation step, thus making 45 possible continuous operation with efficient separation of gluten, and avoiding starch losses and practical difficulties which a draw-off of "middlings" would occasion. Since in this instance the step of flotation is interposed in the return cir- 50 55

cuit, the material returned by way of line 18 is largely freed of gluten, and is substantially unfoamed.

In Fig. 2 I have shown a modified manner in which the step of flotation is associated with the centrifugal separation. In this case the return of a major part of the underflow received by volute 16 occurs directly within the centrifuge machine by way of line 18, while a part of this foamed underflow is diverted thru pipe 21 for flotation. Such an arrangement does not subject the underflow to flotation before being returned to the centrifuge, but it enables variations in the underflow to be immediately reflected in variations in the return, thus affording better inherent stability.

I claim:

1. In a process of the character described for the production of starch from wet starch bearing feed material containing gluten and fibrous material, the steps of centrifugally separating the feed into a starch underflow and a gluten overflow containing the majority of the fibrous material from the feed, and then subjecting the underflow to flotation for the further removal of gluten.
2. In a process of the character described for the production of starch from wet starch bearing feed material containing gluten, the steps of removing a gluten overflow from the feed material by centrifugal separation while simultaneously frothing the starch underflow, and then separating further gluten from the frothed starch underflow by flotation.
3. In a process of the character described for the production of starch from starch bearing feed material containing gluten and fibrous material, the steps of centrifugally separating the feed into a frothed starch underflow and a gluten overflow containing the majority of the fibrous material from the feed, and subjecting the frothed underflow to flotation for the further removal of gluten.
4. In a process of the character described for the production of starch from wet starch bearing feed material containing gluten and fibrous material, the steps of centrifugally separating

the feed into a starch underflow and a gluten overflow containing the majority of the fibrous material from the feed, said step being characterized by the fact that a portion of the underflow is continuously returned to the zone of centrifugal separation, and separating further gluten from the underflow by flotation.

5. In a process of the character described for the production of starch from wet starch bearing feed material containing gluten and fibrous material, the steps of separating the feed into a starch underflow and a gluten overflow containing a majority of the fibrous material, by centrifuging, said centrifuging being characterized by the continuous return of a portion of the underflow back to the zone of separation, and being also characterized by a frothing of the underflow, and effecting further removal of gluten from the underflow by flotation.

6. In a process of the character described for effecting separation between starch and gluten in wet starch bearing material like mill starch, centrifuging the mill starch to form a frothed starch underflow and a gluten overflow, directly delivering the frothed underflow to a body of the same where the frothed component thereof is floated off, continuously returning defrothed starch from said body to said centrifuging operation, and removing starch from said body for final delivery at a rate substantially less than the rate of return.

7. In a process of the character described for the treatment of mill starch or like starch bearing material containing fibrous material together with starch and gluten, centrifuging the mill starch to form a frothed starch underflow and a gluten overflow which contains substantially all of the fibrous material, directly delivering the frothed underflow to a body of the same where the frothed gluten component thereof is floated off, continuously returning defrothed starch from said body to said centrifuging operation, and removing starch from said body for final delivery at a rate substantially less than the rate of return.
